Attorney.

UNITED STATES PATENT OFFICE

JULIUS JONAS, OF BADEN, SWITZERLAND, ASSIGNOR TO AKTIENGESELLSCHAFT BROWN BOVERI & CIE, OF BADEN, SWITZERLAND, A JOINT STOCK COMPANY OF SWITZERLAND

ELECTRIC ARC FURNACE

Application filed January 31, 1931, Serial No. 512,680, and in Germany February 1, 1930.

For operating a plurality of electric arc furnaces it has hitherto been necessary to use separate transformers for feeding the individual furnaces, as it was regarded as impossible to operate reliably in parallel several furnaces from a common transformer. For through the short-circuiting of the transformer consequent on electrodes of one furnace coming into contact with one another, the other furnaces will also be without voltage and, on the electrodes being separated till the current is interrupted, the transformer, on account of the reduction in the ampere turns, has such a considerable stray field that the current of the other furnaces is choked to a very considerable extent.

The present invention relates to a method of and means for operating a plurality of flame arc furnaces fed in parallel from a common transformer over rectifiers, by which this disadvantage is overcome.

According to the invention this is effected by each flame arc furnace being fed from a separate secondary winding and by the secondary windings disposed on a common transformer core being extensively subdivided and the winding parts being intimately intermixed, and furthermore by the two end terminals of each of the secondary windings being connected to the corresponding rectifier anodes over choking coils which are so interlinked that the successive half waves of current of opposite phase of the interlinked chokes magnetize their common iron core in the opposite sense, the flame arc furnaces associated with the secondary windings being connected up in a known manner between the centre point of the secondary windings and the rectifier cathode.

In the accompanying drawing Fig. 1 illustrates, in schematic fashion, one embodiment of the invention wherein a plurality of electric arc furnaces are supplied from separate rectifier elements fed from the common current supply transformer; and Fig. 2 illustrates, also in schematic fashion, another embodiment of the invention wherein the separate rectifier elements of Fig. 1 are combined in a single rectifier.

Referring now to the drawing by char-

acters of reference and considering first the invention according to Fig. 1, a_1 and a_2 are flame arc furnaces working in parallel, which are fed over the rectifiers b_1 , b_2 from the common transformer c . The transformer has 55 two secondary winding d_1 , d_2 , which are extensively subdivided and are disposed, intimately intermixed, on the common transformer limb opposite the primary winding. Each of the secondary windings d_1 , d_2 feeds a 60 rectifier b_1 , b_2 , the end terminals of the secondary windings being connected over the interlinked choking coils e_1 , e_2 to the associated rectifier anodes. The centre points of the secondary windings are connected to 65 the electrodes of the flame arc furnaces, the other electrodes being connected to the cathodes f_1 , f_2 of the rectifiers. A steadyng choke g is preferably interposed in the primary circuit of the feeding transformer. 70

The interlinked choking coils are so designed that, in the case of contact being established between the electrodes of one furnace, that is to say in the case of a short circuit, they can take up the full voltage of the 75 secondary winding, without the magnetizing current assuming a value which would endanger the operation of the other furnace. The intermixing of the parts of the secondary windings is preferably carried so far that 80 on the circuit of one furnace being interrupted, there will be no appreciable choking of the current of the second furnace.

Instead of using a separate rectifier for 85 each of the flame arc furnaces working in parallel, a common rectifier having a suitable number of anodes may of course be used. For example, as shown in Fig. 2 of the drawing, the two rectifiers b_1 , b_2 may be replaced by the single rectifier b having a single cathode f to which the lower electrodes of the furnaces a_1 , a_2 are multiply connected. The elements, connections and operation of Fig. 2 being otherwise as shown and described with respect to Fig. 1 of the drawing. 90

Having now particularly described and ascertained the nature of my said invention and in what manner the same is to be performed, I declare that what I claim is:— 95

1. In an electric furnace system, the com- 100

bination of an alternating current supply line, a transformer having a plurality of independent mid-tapped windings each divided into a plurality of sections and the 5 respective sections of said windings being interlarded, a plurality of flame-arc electric furnaces each having a pair of co-operating electrodes, rectifying means, means comprising one of said windings and said rectifying 10 means for supplying direct current from said line to one of said furnaces, and means comprising another of said windings and said rectifying means for supplying direct current from said line to another of said furnaces.

2. In an electric furnace system, the combination of an alternating current line, a plurality of electric flame-arc furnaces each having a pair of cooperating electrodes, electric 20 current rectifying means, and a transformer comprising a plurality of independent mid-tapped windings each divided into a plurality of sections on each side of the mid-tap thereof and the end terminals thereof 25 of being connected with the said rectifying means to supply current thereto from said line for conversion into direct current and the supply thereof to the said pairs of electrodes to establish and maintain an arc there- 30 between, one electrode of each of the said pairs being connected with the said rectifying means and the other electrode thereof being connected with a different one of said mid-taps, and the respective sections of said 35 windings being interlarded to thereby limit the rise of the inductance of any one thereof upon the occurrence of an interruption of the arc between the electrodes of the furnace connected with another of said windings.

40 3. In an electric furnace system, the combination of an alternating current line, a plurality of electric flame-arc furnaces each having a pair of cooperating electrodes, an electric current rectifier, and a transformer 45 comprising a plurality of independent mid-tapped windings each divided into a plurality of sections and the end terminals thereof being connected with said rectifier to supply alternating current thereto from said 50 line for conversion into direct current and the supply thereof to the said pairs of electrodes to establish and maintain an arc therebetween, one electrode of each of said pairs being connected with the said rectifier 55 and the other electrode thereof being connected with a different one of said mid-taps, and the respective sections of said windings being interlarded to thereby limit the rise of the inductance of any one thereof upon 60 the occurrence of an interruption of the arc between the electrodes of the furnace connected with another of said windings.

4. In an electric furnace system, the combination of an alternating current line, a 65 plurality of flame-arc furnaces each having

a pair of cooperating electrodes, an electric current rectifier for each of said furnaces, and a transformer comprising a plurality of independent mid-tapped windings equal in number to and separately connected with the said rectifiers to supply the latter with alternating current from said line for conversion into direct current and the supply thereof to the said electrodes of the associated ones of said furnaces to establish and 70 maintain a flame-arc between such electrodes, each of said windings being divided into a plurality of sections on each side of the mid-tap thereof and the sections of the respective windings being interlarded to limit the 75 rise of inductance of any one thereof upon the occurrence of an interruption of the arc between the electrodes of a furnace connected with another of said windings.

5. In an electric furnace system, the combination of an alternating current line, a plurality of electric flame-arc furnaces each having a pair of cooperating electrodes, a rectifier for each of said furnaces having a cathode and a pair of anodes, a transformer comprising a primary winding connected with said line and a plurality of independent mid-tapped secondary windings corresponding in number to said rectifiers and having the end terminals thereof connected with the 90 anodes thereof to supply alternating current from said line therefor for conversion thereby into direct current and the supply thereof to the electrodes of the corresponding ones of said rectifiers to cause the simultaneous flow 95 of an arc between the said electrodes thereof, the said secondary windings being divided into a plurality of sections on each side of the said mid-tap thereof and the respective sections of said windings being interlarded 100 to prevent such decrease of flow of current therethrough as would effect interruption of the arc between the electrodes of the furnace connected therewith upon the interruption of the arc between the electrodes of a furnace connected with another, and a reactance 105 included in each of the said connections between the said secondary windings and the said anodes operative to limit the flow of current therethrough upon the occurrence of direct contact of the electrodes of the furnace connected therewith.

6. The combination with a plurality of flame-arc furnaces each having a plurality of cooperating electrodes, and an alternating current line, of an electric current rectifier for each of said furnaces, a transformer having a plurality of windings corresponding in number to and separately connected with the said rectifiers operative to supply the latter with alternating current from said line for conversion into direct current and the supply thereof to the said electrodes of the associated one of said furnaces to establish and maintain a flame-arc between such 120 125 130

electrodes, each of said windings being divided into a plurality of sections and the sections of the respective windings being interlarded to limit the rise of the inductance of
 5 any one thereof upon occurrence of an interruption of the arc between the electrodes of a furnace connected with another of said windings, and reactor means included in the connections between said rectifiers and the
 10 said windings to stabilize the said arcs.

7. The combination with a pair of flame-arc electric furnaces each having a pair of cooperating electrodes, and an alternating current line, of an electric current rectifier
 15 for each of said furnaces, each rectifier comprising a cathode and a pair of anodes, a transformer having a primary winding connected with said line and a pair of secondary windings each having a mid-tap and being
 20 divided into a plurality of sections on each side of the mid-tap thereof, the sections of the respective windings being interlarded and the terminals thereof opposite to the said mid-tap being separately connected with
 25 the anodes of one of said rectifiers to supply the latter with alternating current from said line for conversion into direct current and the supply thereof to the said electrodes of the associated one of said pair of furnaces to
 30 establish and maintain a flame-arc between such electrodes, the electrodes of the said furnaces being connected respectively with the cathode and the mid-tap of the associated said rectifier and secondary winding, and a
 35 pair of reactance coils arranged about a common magnetizable core included in said connections between each of the said secondary windings and the said anodes of the associated rectifier to thereby limit the magnetization of the
 40 core of said transformer upon the occurrence of direct contact of the said cooperating electrodes, the connection of the said coils of a pair with respect to each other being such as to effect magnetization of the
 45 said common core in the opposite sense.

In testimony whereof I have hereunto subscribed my name this 20th day of January
 A. D. 1931.

JULIUS JONAS.
